UNITED STATES PATENT OFFICE.

WILLIAM H. WINSLOW, OF RIVER FOREST, ILLINOIS, ASSIGNOR OF ONE-HALF TO
CHARLES A. BROWN, OF HINSDALE, ILLINOIS.

CARBURATION.

1,312,660.

Specification of Letters Patent.

Patented Aug. 12, 1919.

Application filed February 12, 1917. Serial No. 147,990.

To all whom it may concern:

Be it known that I, WILLIAM H. WINSLOW, a citizen of the United States, residing at River Forest, in the county of Cook 5 and State of Illinois, have invented a certain new and useful Improvement in Carburation, of which the following is a full, clear, concise, and exact description, reference being had to the accompanying drawings, forming 10 a part of this specification.

My invention relates to an improved method of and means for carburation.

In preparing the proper fuel charge for internal combustion engines and the like, it 15 is desirable to produce as intimate a mixture as possible of fuel and air to secure high thermal efficiency and clean combustion.

The earliest type of internal combustion engines were operated upon a mixture of air 20 and fuel gas. Carburation was easy because of the natural tendency for the gases to mix because of their high fluidity, small inertia and because of the tendency for diffusion.

The desirability of employing liquid or 25 solid fuel was at once recognized because of the requirement for mobility.

Perhaps the first attempt at the use of liquid fuel was made by carbureting the air by drawing the same through a tube sub- 30 merged in a tank of liquid fuel. For ob-
vious reasons this was not practical. The more volatile constituents were first evapo-
rated and the remainder would finally be a residue of high boiling point which was dif-
ficult to vaporize. It was soon proposed to 35 employ the "mixing valve". This is an early form of carbureter in which the intake of the engine is closed off by a valve body. This valve body when opened by suction un-
40 covers a port or jet from which the fuel issues under a certain head and is injected into the current of air.

This form of device was fairly satisfactory for fuel that was easily vaporized. It 45 is highly wasteful of fuel and can make no compensation for the speed of the engine.

The simple jet carbureter was soon pro-
posed. This provided a jet or nozzle in the 50 intake passage of the engine, fuel being maintained at substantially the top of the jet by a float controlled or other level maintain-
ing device. This device was fairly success-
ful for easily vaporizable fuel though it could make no compensation for engine 55 speed.

The final form in which the carbureter for easily vaporized fuels appears is the constant level jet with compensating means for engine speed and for starting condition.

But at this stage of the development of 60 the art the necessity arises for using fuel of a much lower degree of vaporizability.

It was recognized that low grades of fuel are so inert to the action of a simple current of air that carburation is substantially 65 impossible by such means. There have recently been developed devices for causing the incoming air to act more intimately upon the fuel as by what is termed air-bled jets and as by employing a plurality of jets and 70 the like.

It appears that this type of fuel is not only difficult to vaporize or atomize but also it is difficult to get a proper mixture such as is necessary for clean and efficient combus- 75

My invention is a departure from the above line of development. My invention aims to provide an improved method of preparing liquid fuel for carburation; an 80 improved method of employing the prepared fuel in carbureting the air of the charge; and an improved method of compensating the mixture for starting and for varying engine speed. 85

A further object distinct from the above aims is the provision of novel means for carrying out each of the above methods.

According to my invention as set out in the first object above, the fuel is prepared for 90 carburation by mechanically "whipping" or "beating" the same much in the way that eggs are whipped or beaten to form a larger bulk or body of an air emulsion of much lower density, greater fluidity and capable 95 of being readily carried into mixture by a current of air.

My invention further teaches according to the second object above an advantageous manner of utilizing liquid fuel for carburation by injecting the air in fine streams into the liquid fuel, the fuel being mechani- 100 cally driven into the fuel charge so that no residue is left. More particularly my invention provides in this aspect a manner of 105 using the fuel prepared as above. This is accomplished by releasing air throughout the extent of emulsion, which air under the suction of the engine expands and further subdivides the fuel to a degree of fineness 110

not heretofore approached. Instead of injecting fuel into the air, I first subdivide the fuel and inject the air into it.

The third object above is attained according to my invention by adding a centrifugal impulse to the suction impulse which moves the air, this centrifugal impulse being effective in greater degree at high engine speed.

For starting purposes, fuel is substituted for a part of the air which is supplied to the engine.

Having disclosed in general terms the nature of my invention, I shall now describe in detail with the aid of the accompanying drawings, one embodiment of my invention to make clear to those skilled in the art a manner or practising the same.

Figure 1 is a longitudinal vertical section of a device embodying my invention;

Fig. 2 is a transverse section on the line 2--2 of Fig. 1; and

Fig. 3 is a general elevational view indicating the manner of applying my invention to an internal combustion engine.

As shown in the drawings, my invention comprises a stationary housing or mixing barrel 1 and a rotor element 2 mounted to rotate in said mixing barrel, and a manifold housing 3.

The central rotating member or rotor 2 comprises a tubular member 4 provided with a disk or flange 5 at its innermost end and being mounted for rotation upon the roller bearings 6 and 7 which are mounted within the hub 8 forming an extension of the main barrel or housing 1.

The rotor 2 is provided with a plurality of short tubes 9 of small diameter which are mounted in apertures in the walls of the rotor 2 as by means of screw threads, these tubes being open from end to end and communicating at their inner end with the interior of the tube 4 and discharging at their outer ends into the barrel 1. In constructing a carburetor of this type I prefer to employ a suitable number of tubes of small diameter whose aggregate area of opening will be substantially equal to or greater than the area of opening of the tube 4. For example:

In constructing the tube 4 of $\frac{1}{4}$ inch diameter inside, I have found that six rows of 16 tubes each provide, when each of the air tubes is $\frac{1}{16}$ inch diameter opening, a total aggregate area approximately equal to the area of the intake tube. It is obvious that the number of tubes in each row and the arrangement of the rows may be varied without departing from the spirit of my invention.

In four of the tubes of each row, preferably in quartered relation, I have added transverse openings about half way down the length of the tube, these openings being drilled at right angles to the run of the tube to introduce a small amount of air at the intermediate portion of the barrel 1 in the mid

zone of the mixing space. In the construction indicated, for a $\frac{1}{4}$ inch diameter tube having an internal diameter of $\frac{1}{16}$ inch, I form the transverse holes 10 of the size of a No. 60 drill. Radially projecting pins 11 are mounted upon the inside of the barrel 1, these pins being of a relatively small diameter, as for example, $\frac{1}{16}$ inch, and lying in rows between the radial tubes 9. The combined action of the stationary pins and the centrifugal mixing tubes 9 is to chop up or whip the contents of the barrel 1 in a very thorough manner. At the outer end of the barrel 1 I have provided a centrifugal spraying or spreading disk 12 which is provided with a curved flange and a plurality of blades 13 lying radially to the flange, this spreading or spraying disk being positioned in front of the fuel jet 14 which opens into the bottom of the barrel 1 as indicated in Fig. 1. The upper end of the jet 14 is directed toward a spraying disk in such a manner that the fuel discharged from the nozzle will strike the spreading disk and will then be spread or sprayed into the space between the barrel 1 and the rotating tube 4. The spraying disk 12 is provided with a hub 15 which is mounted upon a reduced part of the tube 4 and rests against a shoulder 16. The lower race 17 of the roller bearing 6 is mounted against the hub 15 upon the reduced part of the tube 4. Between the race 17 of the roller bearing 6 and the race 18 of the roller bearing 7, I have provided a spacing ring 19 which carries a felt washer 100 or ring 20. These parts are held in place by a lock nut 21 which is threaded upon the reduced part of the tube 4. A driving wheel 22 is also mounted upon the tube 4 and is held in place by a second lock nut 23. The wheel 22 may be in the form of a driving pulley or in the form of a gear for imparting suitable motion to the rotor 2. The rotor may be driven by a solid shaft from the opposite end or by any other means found desirable whether driven by the engine or a separate motor.

The open end of the rotating tube 4 is connected as by means of the tube 24 to a hot air box heated by the exhaust manifold of the engine.

The barrel 1 and the manifold casing 3 are provided with co-operating flanges 25 and 26 which are fastened together by suitable screws 27. The flange 25 is formed upon the outer edge of the bell shaped portion 28 which connects by means of a reduced portion 29 to the vertical tube 30. This tube is connected by a suitable flange 31 to the intake pipe or manifold 32 of the engine. The usual throttle 33 and means to control the same 34 is provided for governing the amount of the fuel charge supplied to the engine. The casing 3 is provided with auxiliary air inlet 35 that is controlled by a

suitable valve 36, said valve being typical of any manually or automatically controlled valve which may be found desirable.

5 The jet 14 is connected by a pipe 37 to the float chamber 38' which is kept constantly supplied with liquid fuel.

10 For the purposes of providing a rich mixture at starting, a tube 38 is introduced into the rotating tube 4, the tube 38 having discharge openings 39 for discharging a quantity of liquid into the end of the tube 4 adjacent the open ends of the centrifugal tubes 9. The tube 38 is connected to the usual priming means which may be in the 15 form of a pump, an auxiliary well or the like.

15 As shown in Fig. 3, the gear 22 may be driven by a gear 41 connected by means of a suitable shaft 42 to a gear 43 lying within 20 the casing 44 and meshing with the pump or cam shaft gear. The shaft 42 may be directly connected to the rotor 2 if so desired.

25 The operation of the device illustrated is as follows:

25 The rotor element 2 is connected directly as by gears or a belt to the moving parts of the engine so that the speed of the rotor corresponds to the speed of the engine. When the engine is started, a small quantity of 30 liquid fuel is discharged to the priming tube 38 into the tube 4. This liquid fuel finds its way through the tubes 9 into the shell or barrel 1 and thus is carried along with the air into the intake manifold and into the 35 cylinders of the engine. It is to be noted that the priming charge thus introduced takes the place of some of the air and tends to produce a rich mixture such as is necessary on starting. At the same time that the 40 engine is started, the suction of the engine causes a discharge of liquid fuel from the nozzle 14 against the spreading or spraying disk 12 and this fuel is whipped or beaten by the rotating and stationary part into a 45 fine emulsion which is easily carried away by the air that comes into the centrifugal tubes 9.

50 During operation of the device, the fuel which enters by way of the nozzle 14 is thrown into the space in which the centrifugal tubes 9 are moving, where, as above explained, the liquid is very violently agitated and at the same time air is introduced at a 55 number of points in fine jets which air, under the influence of suction, easily carries away this intimate mixture of fuel and air to supply the necessary charge to the engine.

50 For higher speeds of the engine and correspondingly higher speeds of rotation of the 60 rotor 2, an additional force is added to the air, namely, the centrifugal or throwing force of the tubes 9, these tubes acting as minute centrifugal pumps tending to move a greater quantity of air into the intake

65 manifold than would be drawn in by the mere suction impulse. The proportioning of the parts may be such as to compensate for any particular type or size of engine. This centrifugal action automatically thins out the mixture as the speed of the engine is 70 increased.

75 Independently of the automatic compensation of the mixture, additional air may enter through the pipe 35 to constitute an auxiliary air supply, if so desired. The three basic conceptions in the operation of a device are apparent from the above. First, whipping, beating or chopping the liquid into an air emulsion. Second, introducing the air in a finely divided space into an 80 agitated mass of liquid, and third, the automatic compensation for engine speeds by giving the air a centrifugal impulse in addition to the suction impulse.

85 The importance of whipping or finely sub-dividing the liquid fuel before the air is injected is readily apparent from the fact that the area of a given quantity is thereby greatly increased and the distance of any particular particle of fuel from the incoming air is thereby vastly diminished.

90 Heating the incoming air is found to be highly advantageous, particularly because of the intimate mixture of the air and fuel. The introduction of heated air in an air 95 emulsion of liquid fuel is peculiarly efficacious for the heavier grades of oils.

95 It is apparent that the invention may be embodied in other forms, and that the proportions may be varied to suit the condition.

100 What I claim is:

105 1. The process of preparing a charge of air and liquid fuel for rapid combustion which consists in whipping the liquid fuel by mechanical impulses and simultaneously subjecting the whipped product to numerous individual jets of air within the whipped product.

110 2. The process of preparing a charge of air and liquid fuel for an internal combustion engine or the like which consists in whipping the liquid fuel by mechanical impulses and then causing numerous fine jets of air to discharge in the mass of whipped fuel.

115 3. The method of mixing air and fuel which consists in mechanically whipping a small quantity of fuel and simultaneously injecting into the mixture a plurality of fine jet streams of air under pressure.

120 4. The method of preparing a proper mixture of air and fuel for higher engine speeds which consists in moving air in a plurality of fine jets into intimate contact with the fuel by suction and simultaneously exerting a force upon the air by centrifugal action caused by the engine.

125 5. The method of mixing air and fuel,

- which consists in mechanically agitating and comminuting a relatively small quantity of fuel and simultaneously introducing air in numerous fine jets throughout the extent 5 of the comminuted fuel.
6. In combination a casing having a discharge outlet, said casing comprising a barrel portion, a rotor in said barrel portion, a jet delivering liquid fuel into said 10 barrel portion upon a portion of said rotor and means on the rotor for mechanically injecting air through said rotor between said jet and the engine manifold.
7. In a carbureter, a barrel or casing, 15 a rotor in said barrel or casing, said rotor comprising a plurality of small diameter tubes and a passage communicating with the atmosphere and said small tubes, said passage being formed in said rotor.
8. In combination a barrel, a rotor in 20 said barrel, said rotor comprising a tube having its inner end closed, said tube communicating with the atmosphere and having a plurality of short tubes of small diameter 25 communicating with the interior of said tube and the interior of the barrel, means for projecting liquid fuel into contact with the rotor and means for driving the rotor.
9. In combination a closed casing adapted 30 to be connected to the intake manifold on an engine, a tube having its inner end closed, said tube projecting into said casing and being rotatably mounted with respect to said casing, a plurality of tubes 35 of small diameter projecting from the walls of said closed end tube, and a plurality of pins mounted upon the interior of said barrel.
10. In combination, an internal combustion 40 engine, and a carbureter for said engine, said carbureter comprising a casing, a rotatable tube in said casing, means mounted on said tube for violently agitating the liquid fuel supplied to said carbureter, means for supplying liquid fuel and projecting the same into contact with the rotor and means connecting said rotatable tube with the shaft of the engine.
11. In combination, a main driving shaft, a carbureter comprising a housing, a rotor in 50 said housing, means for supplying liquid fuel to said housing, means on said rotor for mechanically agitating the fuel in said housing and means connecting said rotor with the main shaft, said rotor comprising a spreading disk against which the fuel is sprayed and an air impelling means for forcing air into intimate mixture with the 55 agitated liquid fuel.
12. In combination, a carbureter housing adapted to be connected to the intake manifold of an engine, a rotating tube projecting into said housing, means for supplying liquid fuel to said housing, said rotating tube 60
- having hollow projecting arms for agitating the liquid fuel and for passing air through said agitated fuel.
13. In a device of the class described, means for supplying liquid fuel, mechanically impelled means for pulverizing said liquid fuel and means connected to said second means for injecting numerous fine streams of air in the mass of pulverized fuel. 70
14. In a carbureter, a barrel or housing having inwardly projecting means, a central tube adapted to be rotated, said tube having short tubes of smaller diameter projecting in rows therefrom, said rows being adapted to pass between said projections on the barrel, said tubes of small diameter communicating with the interior of said central tube, and means for rotating said central tube. 75
15. In combination, a barrel having projections upon the interior surface thereof, a central tube adapted to be rotated with respect to said barrel, said central tube having its inner end closed, an outlet for said barrel adjacent said closed end, and a flange secured to the closed end of said central tube, a plurality of projecting members upon said rotating tube and means for supplying liquid fuel to said barrel at a point remote from said flange. 80
16. In combination, a barrel having an outlet adapted to be connected to an engine manifold, said barrel having a plurality of inwardly extending projections, a central tube rotatably mounted adjacent said barrel, a plurality of short tubes projecting from said central tube, a flange closing the inner end of said central tube, a spreading disk on said central tube and a fuel jet adapted to discharge liquid against said spreading disk. 85
17. In combination, a casing having an inlet and an outlet, a rotor in the casing, said rotor being adapted to be positively driven, said rotor having a disk with upturned edges adapted to throw the liquid fuel outward by centrifugal action, separate air impelling means connected to and axially displaced from the disk for introducing air into the casing and forcing air into contact with the liquid fuel and a fuel inlet for projecting the fuel against said disk. 90
18. In combination, a casing having inlet and outlet, a rotor in the casing, a shaft for positively driving said rotor, said rotor having a disk adapted to throw the liquid fuel outward by centrifugal action, centrifugal air impelling means independent of the disk and axially displaced from the disk for forcing air into the casing and into intimate contact with the liquid fuel and a fluid fuel inlet for projecting liquid fuel against said disk. 105
19. In a carbureter for internal combustion engines and the like, a barrel, a fuel jet in the barrel, means adapted to be mechanically driven by the engine to whip or pul- 110
- 120
- 125
- 130

verize the fuel issuing from the jet, and means connected to said first means for injecting air under pressure in numerous fine streams into the mass of pulverized fuel.

5 20. In a carbureter, a barrel, a suction-controlled fuel jet in the barrel, means adapted to be mechanically driven to whip or pulverize the fuel issuing from the jet, and means connected to said first means for introducing air under pressure and injecting the same into the mass of pulverized fuel.

10 21. The method of mixing air and fuel which consists in mechanically pulverizing a small quantity of liquid fuel and simulta-

neously injecting in accordance with the 15 speed of the engine a plurality of fine streams of air under pressure into the mass of pulverized fuel.

22. The method of compensating the mixture produced by a carbureter of the suction 20 type for higher engine speeds, which consists in mechanically forcing air into the mixture in accordance with the speed of the engine.

In witness whereof I hereunto subscribe my name this 8th day of February, A. D. 25 1917.

WILLIAM H. WINSLOW.
